TREE STAND

Herman M. Austenson, Rte. 1, Box 423, Sumner, Wash.

Filed Sept. 5, 1961, Ser. No. 66,607

Term of patent 14 years

(Cl. D35—3)

FIG. 1

FIG. 2

FIG. 3

FIGURE 1 is a top perspective view of a tree stand embodying my new design;

FIGURE 2 is a top plan view thereof; and

FIGURE 3 is a side elevational view thereof.

I claim:

The ornamental design for a tree stand, substantially as shown.
